BUILDING BLOCKS.
APPLICATION FILED DEC. 13, 1921.

Patented Dec. 5, 1922.

2 SHEETS—SHEET 2.

Orde B. Billman Attorney

UNITED STATES PATENT OFFICE.

EMIL C. SIXTA, OF CLEVELAND, OHIO.

BUILDING BLOCKS.

Application filed December 13, 1921. Serial No. 521,983.

To all whom it may concern:

Be it known that I, EMIL C. SIXTA, a citizen of the United States, residing at Cleveland, in the county of Cuyahoga and State of Ohio, have invented certain new and useful Improvements in Building Blocks, of which the following is a specification.

My invention relates to improvements in building blocks, and more particularly to that class or type which are adapted to interlock with each other when the blocks are laid or set up in the completed structure.

The primary object is to provide a generally improved building block or unit of the class indicated which will be exceedingly simple in construction, cheap of manufacture, and efficient in use.

A further object is the provision of improved building blocks for use in the amusement and instruction of children by the provision of a series of blocks of a novel construction which may be joined together in various ways to produce different kinds of building structures and which may be arranged in different ways in the same structure to vary the ornamental appearance thereof.

A still further object is the provision of novel interlocking means requiring the blocks to be laid or set up in a novel manner, so that when the structure is completed the same may be lifted up and moved from one position to the other without breaking up or disarranging the blocks or units and when it is desired to tear down the same requiring that the blocks be removed in substantially reverse order to the building up of the same in the original structure.

With the above mentioned and other ends in view, the invention consists in the novel construction, arrangement, and combination of parts, illustrated in some of its embodiments in the accompanying drawings, and particularly pointed out in the appended claims.

Referring to the drawings, forming a part of this specification, Figure 1 is a front elevation of a building built up with my improved interlocking blocks or units.

Fig. 2, a perspective view of one of the blocks or units in the specific form of a cornice block and illustrating in particular the subjacent hooked projections which interlock with subjacent blocks or units.

Fig. 3, a perspective view of one of the regular building blocks or bricks.

Fig. 4, a perspective view of a plurality of regular blocks laid in assembled interlocking relation to form a side wall. 60

Fig. 5, a perspective view of one of the base blocks for use in the initial formation or building up of a suitable building.

Fig. 6, a perspective disassembled view of the window forming blocks or units and which by extension may form door frames. 65

Fig. 7, an enlarged vertical cross sectional view of a completed structure, including floor and partition forming units.

Fig. 8, a fragmentary view of a roof structure. 70

Fig. 9, a top plan view of one of the key bar forming blocks or units for the roof structure.

Fig. 10, a side view of one of the filler blocks for use in obtaining a bar or beam, or the like, of any desired length. 75

Fig. 11, an end view of the same.

Fig. 12, a cross sectional view of a pair of superposed blocks. 80

Fig. 13, a side elevation of a pair of blocks or units arranged in interlocking relation to form a corner.

Fig. 14, a plan view of an abutment block provided with tenons to enter into mortise 85 openings in adjacent parts to be supported.

Similar numerals of reference designate like parts throughout all the figures of the drawings.

Upon reference to the drawings, it will be 90 seen that the building structure is made up of a plurality of blocks or units suitably arranged and interlocking, as hereinafter described. The various building blocks or units may be of any suitable and convenient material and likewise of any suitable and convenient form. For example, certain blocks may take the specific form of suitably ornamented base blocks 1, to form the initially laid base or foundation of the structure and suitable cornice forming blocks 2, the windows being formed by means of side bar forming blocks 3, adapted to interlock with suitable projections or tenons 4^a and 4^b of the transverse frame forming blocks 4. 95

In the present instance, the base window block 4 is provided with subjacent hook shaped projections 4^c, (corresponding to the hooked projections on the regular blocks or units hereinafter described) adapted to in- 100 105 110

terlock with the flanged recesses of the subjacent regular blocks or units 5.

It will be seen that each block or unit 1, 2 or 5 is provided with oppositely arranged recesses and projections adapted to receive and interlock with the corresponding projections and recesses of superposed and subjacent blocks, respectively, when set up in proper assembled position, as hereinafter more fully referred to.

It will be seen that each regular block 5 is provided on its top with a main or undercut recess 5^a, extending from the rear edge of the block and terminating in a second or reduced recess 5^b, thereby forming under cut corner flanges or projections 5^c. As a means of interlocking a superposed block or unit with the under cut projections 5^c of the subjacent units, each unit or block is provided with depending projections 5^d, said projections 5^d, in the present instance, being spaced apart to form an intervening tenon receiving recess 5^e, and being provided with horizontally extending projections 5^f, adapted to enter beneath the projections 5^c of a pair of subjacent blocks when laid, as shown most clearly in Fig. 4 of the drawings. It will thus be noted that the parts 5^b and 5^c of the projections form substantially hook shaped projections facing towards the outer sides of the wall and that in laying up the blocks each block to be placed in position will be initially placed slightly to the rear of the subjacent blocks and moved forwardly with the front edge thereof flush with the two subjacent blocks, thereby carrying the tongues or free ends of the hooks 5^c beneath the corner projections 5^e of the subjacent blocks. Upon reference to Figs. 2, 7 and 8 of the drawings it will be seen that the cornice block 2 lacks the under cut recesses 5^a, 5^e and projections 5^c formed in the top portions of the regular blocks but is provided with the corresponding hook shaped portions 2^d and 2^f, with the tenon receiving recess 2^e. Upon reference to Fig. 5 it will be seen, on the other hand, that the base block 1, lacks the depending hook shaped projections but is provided with a main recess 1^a and second recess 1^b, forming corner projections 1^c, and corresponding to the parts 5^a, 5^b and 5^c of the regular blocks. Similar remarks apply to the transverse window or door frame blocks 4, it being noted that the upper block 4 is provided with a main undercut recess 4^a, and a second or smaller recess 4^b, forming the undercut corner projections 4^c, and in this connection it will also be noted that the blocks 4 are provided with tenons, adapted to enter into recesses or mortise openings 3^a, in the side bar forming blocks 3. The side bar forming blocks 3 may be provided with recesses 3^b, on their inner sides to receive the sash frames and by the use of filler blocks 6, as shown in Figs. 10 and 7

of the drawings, such blocks 3 may be extended to form the side bars of the door frames. Somewhat similarly shaped bar forming blocks 7, provided with grooves 7^a, may be used in forming partition wall supporting bars and horizontal floor supporting bars or joists, as shown in Fig. 7 of the drawings. In such instance it will be also seen that filler blocks 6, such as shown in Figs. 10 and 11, are utilized in forming the joints or connections between the vertical horizontally extending wall supporting bars or beams and that similarly shaped filler blocks may be used in making desired lengths or extensions of such beams, the filler blocks 6 being provided with tenons 6^a, adapted to enter into mortise openings in the adjacent blocks to be supported.

Referring to Fig. 8 of the drawings, it will be seen that roof or rafter forming blocks 8, are provided, said blocks 8 being provided with roof or board receiving recesses 8^a, in their sides and being provided at their ends with mortise openings 8^b, to receive tenons 9^a and 10^a, of key forming blocks 9, and abutment blocks 10, as shown. It will be seen that the abutment blocks 10 are provided with tenons 10^b, adapted to enter the tenon receiving mortises 5^e, of the regular blocks and between the hooks 2^d and 2^f, of the cornice blocks.

Having thus described some of the embodiments of my invention, without having attempted to set forth all the forms in which it may be made, or all the modes of its use, what I claim and desire to secure by Letters Patent, is,—

1. A building block having spaced hook shaped projections on its under side extending in a common direction from one edge toward the other.

2. A building block having hook shaped projections on its under side spaced apart and extending in a common direction from one side forming an intervening tenon receiving mortise.

3. A building block having an undercut recess extending transversely from one of the longitudinal edges thereof and intersecting its top forming spaced flanges to interlock with a superposed block.

4. A building block having undercut recesses on its top side forming corner flanges and provided with depending hook shaped projections adapted to interlock with the corner flanges of subjacent blocks.

5. A building block having depending hook shaped projections on its under side extending in a common direction toward its face and spaced apart forming a rear mortise to receive a tenon of an adjacent block.

6. A building block having inset and offset locking members on its top and under sides, respectively, and extending from the rear face of the block to receive and inter-

- lock with corresponding locking members of superposed and subjacent blocks, respectively.
7. A building block having undercut recesses on its top side and extending from the rear face thereof forming inset flanges and provided with depending undercut projections adapted to interlock with similarly located inset flanges of subjacent blocks.
10. 8. A building block having undercut recesses and depending hook shaped projections on its top and under sides and extending from the rear face thereof to interlock with corresponding projections and recesses 15 of superposed and subjacent blocks, respectively.
9. A building block having oppositely arranged undercut recesses and projections on its upper and lower sides and extending 20 from the rear face thereof adapted to receive and interlock with corresponding undercut projections and recesses of superposed and subjacent blocks, respectively.
10. A building block having oppositely arranged and extending flanged recesses and hook shaped projections adapted to receive and interlock with correspondingly arranged and extending hook shaped projections and flanged recesses of superposed and 25 subjacent blocks, respectively, when set up.
11. A building block having undercut recesses and hook shaped projections on its top and under sides, respectively, said undercut recesses forming undercut corner 30 flanges in alignment with said hook shaped projections and being spaced apart forming rear mortise openings to receive a tenon of an adjacent block.
12. A building block having depending 35 hook shaped projections on its under side extending toward its face and spaced apart forming conjointly with a subjacent block a mortise to receive a tenon of an adjacent block on the inner side of a wall formed 40 from said blocks.
- 45 13. A building block having undercut recesses and hook shaped projections extend-
- ing outwardly on its top and under sides, respectively, said undercut recesses forming undercut flanges in vertical alignment with 50 said hook shaped projections and being spaced apart forming a mortise to receive a tenon of an adjacent block.
14. A building block having main and supplemental recesses on its top extending 55 from the rear thereof and forming corner projections, said block being provided on its lower side with spaced hook shaped projections extending towards the face of the block to enter into the recesses of a subjacent 60 block from the rear thereof and to interlock with said corner projections when in place.
15. A building block having undercut recesses and projections on its top and under sides to receive and interlock with corresponding undercut projections and recesses 65 of superposed and subjacent blocks, respectively, said undercut recesses and projections being spaced apart to form mortise recesses between the blocks on the inner sides 70 thereof for tenons of adjacent blocks.
16. A building block having main and supplemental recesses on its top extending from the rear side thereof and forming overhanging corner projections, said block 75 being provided on its lower side with spaced hook shaped projections extending towards the face of the block to enter into the recess of a subjacent block from the rear thereof and to interlock with said corner 80 projections when in place.
17. A building block having undercut recesses and projections on its top and under sides to receive and interlock with corresponding undercut projections and recesses 85 of superposed and subjacent blocks, respectively, said undercut recesses forming spaced projections to receive and interlock with projections of a superposed block and said projections being spaced to form mortises to receive tenons of adjacent blocks.

In testimony whereof I have affixed my signature.

EMIL C. SIXTA.
